19 Claims. (Cl. 35—63)

This invention relates to chalkboards and tackboards and particularly to mounting and setting systems therefor.

As the result of a large surge in preschool age child population shortly after World War II there was a need for substantial additional kindergarten and grade school building facilities. These facilities were built and included chalkboards and tackboards where desired. The chalkboards and tackboards were set at a short distance above the floor for use by children of these ages. For example in kindergarten rooms the lower edges of the chalkboards may be set 20 inches above the floor.

As this large group of children progressed through the various school grades the demand for kindergarten and lower grade school facilities relatively decreased whereas the need for higher grades and high school facilities increased at a relatively greater rate. In many communities it was desirable to convert kindergarten and lower grade school facilities to higher grade or high school facilities. To accomplish this it was necessary to change the position of the chalkboards and tackboards upon the walls. For example in the upper grades and high school the lower edges of the chalkboards are positioned 30 to 32 inches above the floor to accommodate the taller children as contrasted with a 20 inch placement of the lower edge of a chalkboard in kindergarten rooms.

Prior chalkboard and tackboard setting systems do not lend themselves to ready movement from one height to another. More specifically, the prior setting systems are fastened to the walls and anchored in such a manner that removal from the walls breaks the chalkboards and tackboards. Often the walls were actually built around the tackboards and chalkboards whereby to necessitate rebuilding or tearing down of wall sections as the case might be to change the height of the chalkboards.

Accordingly, it is an important object of the present invention to provide an improved chalkboard and tackboard setting system.

More specifically, it is another object of the present invention to provide an improved chalkboard and tackboard setting system in which the height of the chalkboards and tackboards can be readily changed upwardly or downwardly to accommodate different sizes of pupils.

Yet another object of the invention is to provide a setting system of the type set forth in which the position of the chalkboard and tackboard on the associated wall can be rapidly and economically changed without injury to the chalkboard and tackboard.

Still another object of the invention is to provide a setting system of the type set forth which is structurally safe and which can be economically and easily installed.

Yet another object of the invention is to provide in a setting system of the type set forth an improved support channel for mounting chalkboards and tackboards.

A further object of the invention is to provide a chalkboard setting system of the type set forth with improved clips.

These and other objects and advantages of the invention will be better understood from the following description when taken in conjunction with the accompanying drawings. In the drawings wherein like reference numerals have been utilized to designate like parts throughout:

FIGURE 1 is a perspective view illustrating the mount-

2

ing system of the present invention with a chalkboard and tackboard mounted thereon, one preferred height being illustrated in solid lines and a readily obtained lower height being illustrated in dashed lines;

FIGURE 2 is an enlarged perspective view with certain portions broken away illustrating the setting system members of the present invention and the manner in which they cooperate with an associated tackboard and chalkboard;

FIGURE 3 is a further enlarged view in vertical section through the top mounting clip and the associated channel of the present invention substantially as seen in the direction of the arrows along the line 3—3 of FIGURE 2;

FIGURE 4 is a further enlarged partial view similar to FIGURE 3 and illustrating the intermediate clip of the present invention and its cooperation with the associated channel substantially as seen in the direction of the arrows along the line 4—4 of FIGURE 2;

FIGURE 5 is a partial and further enlarged view in vertical section illustrating the bottom clip and its cooperation with the supporting channel substantially as seen in the direction of the arrows along the line 5—5 of FIGURE 2;

FIGURE 6 is an enlarged view in perspective with certain parts broken away illustrating a support channel of the present invention;

FIGURE 7 is an enlarged perspective view of a top clip of the present invention;

FIGURE 8 is an enlarged perspective view of an intermediate clip of the present invention;

FIGURE 9 is an enlarged perspective view of a bottom clip of the present invention; and

FIGURE 10 is a perspective view illustrating the mounting of a chalkboard by means of the setting system of the present invention and illustrating in dashed lines the positioning of the chalkboard at an elevated height with respect to the original installation position.

Referring particularly to FIGURE 1 of the drawings, there is shown a chalkboard and tackboard installation generally designated by the numeral 20 and made in accordance with and embodying the principles of the present invention. Installation 20 has been shown as having been made upon a vertical wall 22 and above an

underlying floor 24. Forming part of the installation are a tackboard generally designated by the numeral 26 and a chalkboard generally designated by the numeral 28. Tackboard 26 and chalkboard 28 are supported on wall 22 above floor 24 by means of the setting system including a plurality of vertically disposed channels 30 mounted on wall 22 and having cooperating top clips 32, intermediate clips 34 and bottom clips 36. There is shown in full lines in FIGURE 1 one preferred position of tackboard 26 and chalkboard 28 which might be such as to

place the lower edge of chalkboard 28 approximately 30 inches from floor 24. The dashed lines illustrate a lower position for tackboard 26 and chalkboard 28, the lower position being achieved by simple and inexpensive changes in the setting of clips 32, 34 and 36 along channels 30 as will be explained more fully hereinafter.

Tackboard 26 includes in general a tack receiving body or surface 38 which is completely surrounded by a pair of horizontally extending frame members 40 and 42 and a pair of vertically extending frame members 44 and 46. Chalkboard 28 includes a chalk receiving or writing surface 48 which is surrounded and bound by a pair of longitudinally extending frame members 50 and 52 and a pair of vertically extending frame members 54 and 56.

The lower edge of chalkboard 28 is also preferably provided with an eraser and chalk holding tray 58.

In mounting tackboard 26 and chalkboard 28 using the

setting system of the present invention, at least two and perhaps three or more support channels 30 may be vertically disposed to mount upon wall 22 as illustrated in FIGURE 1 of the drawings. A clip 36 is then positioned on each of channels 30 to receive the lower frame member 52 of chalkboard 28 at the desired height. Intermediate clips 34 are then placed in position on each of channels 30 to engage the upper frame member 50 of chalkboard 28. The intermediate clips 34 also engage the lower frame member 42 to hold and support tackboard 26. The assembly is completed by a top clip 32 mounted on each of channels 30 and engaging the top frame member 40 of tackboard 26.

Referring particularly to FIGURES 2 through 6 of the drawings, the construction of the channels or standards 30 will be described in detail. Channel 30 includes a main wall or web 60 which may be for example eight feet in length and approximately one inch in width. Formed on the longitudinally extending edges of wall 60 are flanges 62 and 64, flanges 62 and 64 extending forwardly from wall 60 in the mounted position and being disposed substantially at right angles therewith. The forwardly disposed edges of flanges 62 and 64 have formed thereon and extending therealong inwardly directed retaining flanges 66 and 68, respectively. The inwardly directed and confronting edges of retaining flanges 66 and 68 may be spaced apart for example a distance of approximately $\frac{3}{4}$ inch. Flanges 66-68 together with flanges 62-64 and web 60 define a pair of spaced apart grooves or raceways that receive and provide a track for various flanges on clips 32 and 34 as will be described more fully hereinafter.

Formed from the body of wall 60 and extending toward retaining flanges 66 and 68 is a plurality of pockets or sockets 70. The outline of a pocket 70 on wall 60 is substantially U-shaped with the upper edge 72 spaced from the adjacent surface of wall 60 and providing a substantially rectangular opening to receive a member therethrough. Preferably the pockets 70 are centered in a horizontal direction upon wall 60 as viewed in FIGURE 6 and are spaced therealong at regular intervals with the upper edges 72 of adjacent pockets spaced apart one inch. Such a structure will permit variations in height of associated chalkboard or tackboard in increments of an inch.

A plurality of apertures 74 is provided along the length of wall 60 to receive fasteners 75 therethrough. Any suitable fastener such as screws, toggle bolts and the like may be used to mount channels 30 upon the associated wall 22. In mounting chalkboards that are four to six feet in length, two channels 30 may be used; in mounting chalkboards six to eight feet long, three standards may be used and in mounting chalkboard eight feet and over four or more channels 30 may be used. Preferably four anchors or fasteners passing through an associated aperture 74 are provided for each channel 30. Care is taken to insure that the standards 30 are positioned with the longitudinal axes thereof disposed vertically and with the upper edge 72 of corresponding pockets 70 lying on a common horizontal line.

The weight of the tackboard 26 and chalkboard 28 is borne primarily by the bottom clip or bracket 36. Clip 36 includes a substantially rectangular body 76 having a width slightly less than the distance between flanges 66-68 to fit therebetween. Struck from body 76 is a pair of locking tabs 78 and 80. Each of tabs 78 and 80 is attached to body 76 along the upper edge of the tab and extends outwardly therefrom and then downwardly substantially parallel to the adjacent surface of clip body 76. The width of tabs 78 and 80 is such as to permit them to be inserted through the opening and into the pockets 70 with the outwardly directed lower surfaces 82 and 84, respectively, resting against and supported by the upper pocket edges 72. The lower surfaces 82 and

84 of the tabs are spaced apart the same distance as adjacent pocket surfaces 72 so that tabs 78 and 80 can be inserted in adjacent pockets 70.

Formed integral with and disposed substantially perpendicular to body 76 is a support flange 86. Flange 86 extends outwardly from body 76 in a direction opposite to that of tabs 78 and 80. Formed integral with the outer edge of support flange 86 is an upturned retaining flange 88. The distance between the facing walls of body 76 and retaining flange 88 is equal to the width of the associated chalkboard frame member 52 so that frame member 52 is received therein to be supported by flange 86. Since flange 86 bears the principal load of the tackboard 26 and chalkboard 28, it is provided with a downwardly extending reinforcing bead 90 provided by deforming a portion of support flange 86 downwardly, reinforcing bead 90 being disposed centrally of support flange 86 and extending in a direction perpendicular to the surface of body 76 and from body 76 to retaining flange 88. An aperture 92 is provided in bead 90 at substantially the midpoint thereof to receive a pointed metal cutting screw 94 for a purpose which will be explained more fully hereinafter.

The construction and operation of intermediate clip or bracket 34 is best illustrated in FIGURES 4 and 8 of the drawings. Clip 34 includes a body 96 which may be substantially rectangular in shape and has a width substantially equal to the width of clip body 76 described above. More specifically, the width of body 96 is such that it can be readily fit between the opposed edges of retaining flanges 66 and 68 on channels 30. Extending outwardly from the sides of body 96 are retaining flanges 98 and 100 which are disposed at an obtuse angle preferably of approximately 145° with respect to the surface of body 96. Flanges 98 and 100 are adapted to be positioned behind channel flanges 66 and 68 whereby to hold clip 34 within channel 30.

Extending outwardly from the lower edge of body 96 and disposed substantially at an angle of 90° therewith is a support flange 102. The width of flange 102 is substantially equal to that of body 96 and extending laterally outwardly from flange 102 is a pair of ears 104 and 106. Depending downwardly from the forward or outer edge of flange 102 is a retaining flange or prong 108. Ears 106 and 108 are provided on the forward edges thereof with upwardly extending retaining flanges or prongs 110 and 112, respectively. Formed substantially in the center of body 96 is an aperture 114.

The top bracket or clip 32 includes a body 116 which is substantially rectangular in shape and has a width substantially equal to that of body 76 of clip 36 and body 96 of clip 34. Extending laterally outwardly from the longitudinally extending edges of body 116 adjacent to the upper end thereof are retaining tabs or flanges 118 and 120. Preferably flanges 118 and 120 are offset rearwardly with respect to body 116 whereby flanges 118 and 120 can fit behind channel flanges 66 and 68 after installation as is illustrated in FIGURES 2 and 3 of the drawings. A second pair of outwardly extending retaining flanges 122 and 124 is formed on body 116 adjacent to the lower end thereof, flanges 122-124 also being offset rearwardly as are flanges 118-120. Formed integrally with the lower end of body 116 and extending forwardly therefrom and at right angles therewith is an overlying or top flange 126 which has a depth equal to the thickness of tackboard frame member 40 and chalkboard frame member 50. Depending downwardly from the forwardly disposed edge of flange 126 is a retaining flange or prong 128 which is adapted to be positioned in front of an associated frame member as for example frame member 40 as viewed in FIGURES 1, 2 and 3.

Means is provided to clamp clip 32 at some desired position along channel 30. To this end an embossed portion substantially circular in shape is provided in body 116 substantially centrally thereof and formed in the center of embossed portion 130 is an aperture 132. Aperture

132 is adapted to receive a metal cutting screw such as screw 134 in FIGURE 3 of the drawings. The top flange 126 of clip 32 is also provided with an embossed or raised portion 136 formed substantially centrally thereof and extending in the same direction as body 116. There is provided in the center of embossed portion 136 an aperture 138 adapted to receive a pointed metal cutting screw 140 (see FIGURES 2 and 3 of the drawings).

The assembly of the setting system will now be described in detail. Standards 30 are first mounted upon the vertical wall 22 by means of suitable fasteners such as screws 75 passing through apertures 74 formed in channel webs 60. Other suitable fasteners such as bolts, toggle bolts or the like may be used. Preferably the standards 30 are positioned with the lower ends thereof disposed on or near the associated floor 24 and are carefully aligned so that the center lines thereof are disposed vertically. Care also is exercised to insure that the upper edges 72 of corresponding pockets 70 on all channels are in horizontal alignment so that the chalkboards and tackboards mounted thereon will be aligned.

A bottom clip 36 is then placed in a selected pocket 70 on each of the standards 30. More specifically, the upper surface of support flange 86 on clip 36 is positioned at the level at which the lowermost edge of the associated chalkboard 28 is to be placed. Mounting of clips 36 in position is accomplished by moving body 76 into channel 30 between flanges 66 and 68. Tabs 78 and 80 are then moved downwardly into adjacent pockets 70 with the lower rearwardly disposed surfaces 82 and 84 of the tabs resting upon edges 72 of the associated pockets. It will be seen from FIGURE 5 that tabs 78 and 80 are securely held in pocket 70 whereby securely to mount bottom clip 36 upon associated channel 30. Care is taken that each bottom clip 36 is positioned at the same level on the various standards 30 which are to receive the chalkboard.

Chalkboard 28 is then placed in position with the lower frame member 52 disposed downwardly in bottom clips 36 and held therein between body 76 and retaining flange 88. Preferably the distance between the adjacent surfaces of body 76 and flange 88 is substantially equal to the width or thickness of frame member 52 as viewed in FIGURE 5. The reinforced support flange 86 is sufficiently strong to hold its share of the weight of chalkboard 28.

The intermediate clips 34 are next placed in position if a tackboard 26 is to be positioned above chalkboard 28 in the finished assembly. During the positioning of clips 34, the chalkboard is completely supported by the bottom clips 36 and care need be exercised only to see that chalkboard 28 is not tipped forwardly at the top away from channels 30. Clips 34 are moved into position by lifting them upwardly to the top of the associated channel 30 and moving them toward wall 22 until the outwardly directed flanges 98-100 lie behind the channel retaining flanges 66 and 68 and within the grooves or raceways formed thereby. Clips 34 can then be slid downwardly within channel 30 with the support flange 102 extending outwardly between the edges of channel flanges 66-68. As can be best seen from FIGURE 4 of the drawings, the distance between the inwardly disposed face of retaining flange 108 and the outer surfaces of flanges 66 and 68 is such as to receive and hold therebetween the top frame member 50 of chalkboard 28. With the intermediate clips 36 in operative position, the chalkboard 28 is fully supported. If for some reason the tackboard 26 is not to be installed immediately, a suitable fastener such as a metal cutting screw can be put through aperture 114 to clamp clips 36 in position to hold chalkboard 28.

Tackboard 26 can next be assembled, any fasteners passing through apertures 114 and clip 36 being first removed. The lower frame member 42 of tackboard 26 is mounted upon clips 36 and moved downwardly between retaining flanges 112 and body 96. The distance between these members is such as to receive and accom-

modate lower frame member 42. Since intermediate clips 36 are free to slide along channels 30, all the weight of tackboard 26 is transferred to the bottom clips 36.

Top clips 32 are next placed in position. This is accomplished by moving each clip 32 to the top of the associated channel 30 and placing the flanges 118-120 and 122-124 behind channel flanges 66 and 68. The clip 32 can then be moved downwardly within channel 30 with top flange 126 extending outwardly between the opposed edges of retaining flanges 66-68. Clips 32 are moved down until the top flanges 126 overlie the top of tackboard frame member 40 with flanges 128 extending downwardly in front thereof. This construction serves to hold tackboard 26 against the associated channels 30. The entire assembly is then locked against vertical movement by placing metal cutting screw 134 in position and tightening it against the web 60 of the associated channel 30.

Means is provided to lock the chalkboard 28 and the tackboard 26 against lateral movement with respect to the standards 30 and clips 32, 34 and 36. Tackboard 26 is locked against lateral displacement by means of the pointed metal cutting screws 140 which pass through embossed portion 136 and bite into the top of frame member 40. Screws 140 therefore positively prevent lateral movement of tackboard 26 with respect to standards 30.

Pointed metal cutting screws 94 are provided on bottom clip 36 to lock chalkboard 28 against lateral displacement. More specifically, screws 94 pass through apertures 92 in the reinforcing beads 90 on clips 30. The pointed ends of screws 94 bite into the bottom frame member 52 and positively prevent lateral displacement of chalkboard 28 with respect to standards 30.

If it is desired to change the position of chalkboard 28 and tackboard 26 upon wall 22, this can be readily done. As viewed in FIGURE 1 of the drawings, there is shown in dashed lines the method in which chalkboard 28 and tackboard 26 can be moved to a lower position. The screws 134 are first loosened and chalkboard 28 and tackboard 26 moved upwardly together with clips 34 and 32 whereby to disengage and free clips 36. Clips 36 are then placed at the desired height by inserting tabs 78-80 into appropriate pockets 70. The chalkboard 28 is then lowered until frame member 52 is again resting upon clip 36 and more specifically support frame 88 thereof. Movement of chalkboard 28 to the lower position will permit intermediate clips 34 and tackboard 26 to be lowered. Top clips 32 will also move downwardly and can then be pressed into final position. If needed or desired, the screws 94 and 140 can be withdrawn after which top clip 32 can be clamped in the final position by tightening screw 134. Screws 94 and 140 can again be tightened to clamp tackboard 26 and chalkboard 28 against lateral displacement.

The described adjustment of the position of the various parts has been accomplished with a minimum of effort and time. There has been no injury to any of the parts and particularly to the relatively expensive tackboard 26 and chalkboard 28. Any desired adjustment in increments of one inch or multiples thereof can be made in the manner described above. The raising of chalkboard 28 and tackboard 26 can be accomplished by the above described method by simply reversing the direction of movement of the parts after lifting the chalkboard and tackboard to the new elevated position.

There is shown in FIGURE 10 of the drawings the manner in which the setting system of the present invention can be utilized to mount the chalkboard 28 without an associated tackboard. The standards 30 are mounted on wall 22 in the manner described with respect to FIGURE 1. Bottom clips 36 are placed in position on channels 30 and chalkboard 28 positioned thereon. Top clips 32 are then moved into channels 30 and downwardly to engage and restrain the upper frame member 40 of chalkboard 28. Upon tightening of screws 134 and

screws 94 and 140, installation of chalkboard 28 is completed.

The position of chalkboard 28 vertically along wall 22 is readily adjusted in a manner similar to that described above. For example if it is desired to raise chalkboard 28 to the position illustrated in dashed lines, screws 94, 140 and 134 are loosened. Chalkboard 28 is then lifted sliding top clips 32 upwardly therewith. Bottom clips 36 are then moved and engaged in the new position and chalkboard 28 lowered thereon. Top clips 32 are next pushed downwardly to engage frame member 40 and are fixed in that position by tightening screws 134. Screws 94 and 140 are then tightened to prevent lateral displacement of chalkboard 28 with respect to standards 30.

The invention has been described above with particular reference to the mounting of chalkboard and tackboards in schools and the like. The invention is equally applicable in other installations. For example the setting system would be useful in art galleries where it is desirable to mount and hang pictures at various adjustable and movable positions upon the display walls. In such an installation the standards 30 could be placed at any desired interval and along the entire length of the display wall. The installation also could be used to advantage in directors' rooms, in display areas to receive bulletin boards and in other display applications such as for advertising meetings, sales meetings, and the like.

It will be seen that there has been provided a chalkboard and tackboard setting system which fulfills all of the objects and advantages set forth above.

Although certain preferred forms of the invention have been shown for purposes of illustration, it is to be understood that various changes and modifications can be made therein without departing from the spirit and scope of the invention. Accordingly, the invention is to be limited only as set forth in the following claims.

We claim:

1. The combination for mounting a chalkboard and the like comprising a pair of elongated standards extending the entire height of the chalkboard and beyond the upper and lower edges thereof, said standards being mounted spaced apart and with the longitudinal axes thereof disposed substantially vertically, a bottom support clip mounted on each of said standards, said support clip having a mounting hook and a chalkboard support flange formed thereon, each of said standards having a plurality of hook receiving members formed thereon along the length thereof receiving said support clip hooks, a chalkboard mounted on the support flanges of said support clips, a channel formed on each of said standards and providing a track, a top clip mounted in each of said standards engaging and holding the upper portion of said chalkboard against said standards, and flanges extending outwardly from said top clip and engaging in said tracks to permit movement of said clips along said standards while preventing movement of said clips laterally outwardly with respect to said standards, said clips being removable after mounting for placement in a new desired position whereby said chalkboard can be changed from one adjusted height to another from time to time as desired.

2. The combination for mounting a chalkboard and the like comprising a pair of elongated standards extending the entire height of an associated chalkboard and beyond the upper and lower edges thereof, said standards being mounted spaced apart and with the longitudinal axes thereof disposed substantially vertical, a bottom support clip mounted on each of said standards, said support clip having a mounting hook and a chalkboard support flange formed thereon, each of said standards having a plurality of hook receiving members formed thereon along the length thereof receiving said support clip hooks, a chalkboard mounted on the support flanges of said support clips, a channel formed on each of said standards

and providing a track, a top clip mounted in each of said standards engaging and holding the upper portion of said chalkboard against said standards, flanges extending outwardly from said top clip and engaging in said tracks to permit movement of said clips along said standards while preventing movement of said clips laterally outwardly with respect to said standards, said top clip having an aperture formed therein, and a screw extending through the aperture in said top clip and engaging said standards to clamp said chalkboard between said top clips and said bottom clips, said clips and said screws being removable after mounting for the placement of said clips in a new desired position whereby said chalkboard can be changed from one adjusted height to another from time to time as desired.

3. The combination for mounting a chalkboard and the like comprising a pair of elongated standards extending the entire height of an associated chalkboard and beyond the upper and lower edges thereof, said standards being mounted spaced apart and with the longitudinal axes thereof disposed substantially vertical, a bottom support clip mounted on each of said standards, said support clip having a mounting hook and a chalkboard support flange formed thereon, each of said standards having a plurality of hook receiving members formed thereon along the length thereof receiving said support clip hooks, a chalkboard mounted on the support flanges of said support clips, a channel formed on each of said standards and providing a track, a top clip mounted in each of said standards engaging and holding the upper portion of said chalkboard against said standards, flanges extending outwardly from said top clip and engaging in said tracks to permit movement of said clips along said standards while preventing movement of said clips laterally outwardly with respect to said standards, said top clip having an aperture formed therein, a screw extending through the aperture in said top clip and engaging said standards to clamp said chalkboard between said top clips and said bottom clips, and screws passing through said bottom clip and said top clip engaging said chalkboard to prevent lateral displacement thereof with respect to said standards, said clips and said screws being removable after mounting for the placement of said clips in a new desired position whereby said chalkboard can be changed from one adjusted height to another from time to time as desired.

4. The combination for mounting a chalkboard and the like comprising a pair of elongated channels extending the entire height of an associated chalkboard and beyond the upper and lower edges thereof, said channels being mounted spaced apart with the longitudinal axes thereof disposed substantially vertical, a plurality of pockets formed on each of said channels throughout the length thereof, a bottom clip for each of said channels, each bottom clip including a hook engaging in one of said channel pockets, a substantially U-shaped portion formed on each bottom clip receiving and retaining the lower edge of a chalkboard, a chalkboard mounted on said U-shaped portion of said bottom clips, a top clip mounted in each of said channels including a retaining flange overlying the forward outer surface of said chalkboard, and means to lock said top clips against said channels to clamp said chalkboard between said top clips and said bottom clips, said clips and said locking means being removable after mounting for placement of said clips in a new desired position whereby said chalkboard can be changed from one adjusted height to another from time to time as desired.

5. The combination for mounting a chalkboard and the like comprising a pair of elongated channels extending the entire height of an associated chalkboard and beyond the upper and lower edges thereof, said channels being mounted spaced apart with the longitudinal axes thereof disposed substantially vertical, each standard including a web, a pair of side flanges extending

outwardly from said web, a pair of retaining flanges formed on the forward edges of said side flanges and extending inwardly toward each other and overlying a part of said web to provide trackways therealong, a plurality of pockets formed in said web and spaced therealong, a bottom clip mounted on each of said standards, each bottom clip comprising a first clip body, a mounting hook formed on said clip body and extending outwardly therefrom to engage one of said pockets, a bottom support flange formed on said first clip body and extending outwardly therefrom in a direction opposite to said hook and between said retaining flanges to support a chalkboard, a chalkboard mounted on said bottom support flanges of said bottom clips, an upturned flange formed on the outer end of said support flange to retain said chalkboard thereon, a top clip mounted in each of said standards, each top clip including a second clip body, lateral flanges extending outwardly from said second clip body and engaging in the track ways on said standards between said web and said retaining flanges, an overlying flange extending outwardly from said second clip body to overlie the top of said chalkboard, a downturned flange formed on the forward edge of said overlying flange and disposed in front of said chalkboard, and means to lock said top clips against said standards to clamp said chalkboard between said top clips and said bottom clips, said clips and said locking means being removable after mounting for placement of said clips in a new desired position whereby said chalkboard can be changed from one adjusted height to another from time to time as desired.

6. The combination for mounting a chalkboard and a tackboard and the like comprising a pair of elongated standards extending the entire combined height of a chalkboard and tackboard and beyond the uppermost and the lowermost edges thereof, said standards being mounted spaced apart in general parallelism and disposed with the longitudinal axes thereof substantially vertical, a bottom clip adjustably mounted on each of said standards in general horizontal alignment to support a chalkboard, a chalkboard mounted on said bottom clips, an intermediate clip mounted on each of said standards and having portions engaging and holding the upper edge of said chalkboard against said standards and portions supporting the lower edge of a tackboard against said standards, a tackboard mounted on said intermediate clips, a top clip adjustably mounted in each of said standards and engaging the upper portion of said tackboard to hold said tackboard against said standards, and means to lock said top clips against said standards to clamp said chalkboard and said tackboard between said top clips and said bottom clips, said clips and said locking means being removable after mounting for placement of said clips in a new desired position whereby said chalkboard and said tackboard can be changed from one adjusted height to another from time to time as desired.

7. The combination for mounting a chalkboard and a tackboard and the like comprising a pair of elongated standards extending the entire combined height of an associated chalkboard and tackboard and beyond the uppermost and the lowermost edges thereof, said standards being mounted spaced apart in general parallelism and disposed with the longitudinal axes thereof substantially vertical, a bottom clip adjustably mounted on each of said standards in general horizontal alignment to support the chalkboard, a chalkboard mounted on said bottom clips, an intermediate clip mounted on each of said standards and having portions engaging and holding the upper edge of said chalkboard against said standards and portions supporting the lower edge of a tackboard against said standards, a tackboard mounted on said intermediate clips, a top clip adjustably mounted in each of said standards and engaging the upper portion of said tackboard to hold said tackboard against said standards, means to lock said top clips against said standards to clamp said chalkboard and said tackboard between said top clips

and said bottom clips, and fasteners mounted on said top clips and said bottom clips engaging said tackboard and said chalkboard to prevent lateral displacement thereof with respect to said standards, said clips and said locking means and said fasteners being removable after mounting for placement of said clips in a new desired position whereby said chalkboard and said tackboard can be changed from one adjusted height to another from time to time as desired.

10 8. The combination for mounting a chalkboard and a tackboard and the like comprising a pair of elongated standards extending the entire combined height of an associated chalkboard and tackboard and beyond the uppermost and the lowermost edges thereof, said standards being mounted spaced apart with the longitudinal axes thereof disposed substantially vertical, a plurality of pockets formed on each of said standards along the length thereof, a bottom clip mounted on each of said standards, each bottom clip having a mounting hook formed thereon engaging in one of said pockets for adjustment along said standard and a chalkboard support flange formed thereon, a chalkboard mounted on the support flanges of said bottom clips, an intermediate clip for each of said standards, each intermediate clip engaging the associated standard and including portions holding the top of said chalkboard against said standards and including portions holding the bottom edge of an associated tackboard against said standards, a tackboard mounted on said intermediate clips, a top clip mounted in each of said standards, each top clip including portions engaging the upper edge of said tackboard to hold it against said standards, and means to lock said top clips against said standards to clamp said chalkboard and said tackboard in adjusted position, said clips and said locking means being removable after mounting for placement of said clips in a new desired position whereby said chalkboard and said tackboard can be changed from one adjusted height to another from time to time as desired.

9. The combination for mounting a chalkboard and a tackboard comprising a pair of elongated standards extending the entire combined height of an associated chalkboard and tackboard and beyond the uppermost and the lowermost edges thereof, said standards being mounted spaced apart with the longitudinal axes thereof disposed substantially vertical, each standard including a web having side flanges formed thereon and a pair of retaining flanges formed on said side flanges and extending inwardly toward each other and overlying a portion of said web to form a pair of trackways, a plurality of pockets formed on said web and spaced therealong, a bottom clip for each of said standards including a body having mounting hooks formed therefrom and extending into said pockets, a U-shaped retaining member formed on said body to engage and hold a chalkboard, a chalkboard mounted on the retaining members of said bottom clips, an intermediate clip for each of said standards including lateral flanges extending into said trackways to hold said intermediate clips on said standards, chalkboard retaining flanges formed on said intermediate clips and engaging said chalkboard, a tackboard mounted on said bottom clips, tackboard engaging flanges formed on said intermediate clip engaging said tackboard, a top clip in each of said channels including a body having lateral flanges formed thereon engaging in said trackway, and a tackboard engaging flange formed on said top clip and engaging the upper edge of said tackboard, said clips being removable after mounting for placement in a new desired position whereby said chalkboard and said tackboard can be changed from one adjusted height to another from time to time as desired.

70 10. A support standard comprising an elongated main wall, said main wall having spaced apart mounting apertures therein side flanges formed on the longitudinally extending edges of said wall and disposed substantially perpendicular thereto and extending in the same direction therefrom, a continuous and imperforate retaining flange

formed on the longitudinally extending free edge of each of said side flanges and extending the length thereof, said retaining flanges being directed inwardly toward each other and parallel to said main wall, said retaining flanges together with said main wall and side flanges providing trackways, and a plurality of hook receiving pockets formed on said main wall and disposed between the opposed edges of said retaining flanges, each pocket having an upper support edge disposed perpendicular to the longitudinal axis of said standard and having a retaining wall extending downwardly therefrom and integral with said main wall and displaced outwardly from the plane thereof toward said retaining flanges to receive a tab therebetween.

11. A support standard comprising an elongated main wall, said main wall having spaced apart mounting apertures formed therein side flanges formed on the longitudinally extending edges of said wall and disposed substantially perpendicular thereto and extending in the same direction therefrom, a continuous and imperforate retaining flange formed on the longitudinally extending free edge of each of said side flanges and extending the length thereof, said retaining flanges being directed inwardly toward each other and parallel to said main wall, said retaining flanges together with said main wall and side flanges providing trackways, and a plurality of hook receiving pockets struck from said main wall and extending therefrom toward said retaining flanges, each pocket having an upper support edge disposed perpendicular to the longitudinal axis of said standard and having a retaining wall extending downwardly therefrom and integral with said main wall and displaced outwardly from the plane thereof toward said retaining flanges to receive a tab therebetween, said pockets being disposed between the opposed edges of said retaining flanges and being spaced at regular intervals along the length of said main wall, the distance between adjacent pairs of said support edges being constant along the length of said standard.

12. A top clip for use with a channel having spaced apart retaining flanges spaced from a connecting wall to provide tracks in cooperation therewith, comprising a body, first side flanges extending outwardly from said body for engagement in the tracks, a second flange disposed substantially perpendicular to said body and extending outwardly therefrom, and a third flange formed on the outer end of said second flange and disposed therefrom in a direction opposite to the direction of said body to engage a member to be mounted on the channel, said body having a fastener receiving opening formed therein, said second flange having a fastener receiving opening formed therein.

13. A top clip for use with a channel having spaced apart retaining flanges spaced from a connecting wall to provide tracks in cooperation therewith and having pockets projecting outwardly from the connecting wall in the same direction as the retaining flanges, said top clip comprising a body, first side flanges extending outwardly from said body for engagement in the tracks, said side flanges being displaced out of the plane of said body to permit said body to clear and to overlie the projecting pockets on an associated channel when said first side flanges are in the tracks, a second flange disposed substantially perpendicular to said body and extending outwardly therefrom, and a third flange formed on the outer end of said second flange and disposed therefrom in a direction opposite to the direction of said body to engage a member to be mounted on the channel, said body having a fastener receiving opening formed therein, said second flange having a fastener receiving opening formed therein.

14. A top clip for use with a channel having spaced apart retaining flanges spaced from a connecting wall to provide tracks in connection therewith said top clip, and having pockets projecting outwardly from the connecting wall in the same direction as the retaining flanges comprising a body, a first pair of side flanges extending outwardly from said body adjacent to one end thereof for engage-

ment in the tracks, second side flanges extending outwardly from said body and spaced from said first side flanges for engagement in the tracks, said first and second side flanges being displaced out of the plane of said body to

5 permit said body to clear and to overlie the projecting pockets on an associated channel when said first and second side flanges are in the tracks, a support flange disposed substantially perpendicular to said body and extending outwardly therefrom in a direction opposite to the displacement of said side flanges, said body having an embossment thereon extending therefrom in the same direction as said support flange and having a fastener receiving opening formed centrally thereof, said support flange having an embossment formed therein extending in the same direction as said body and having a fastener receiving opening formed therein, and a retaining flange formed on the outer end of said support flange and extending therefrom in a direction opposite to the direction of said body.

20 15. An intermediate clip for engaging and mounting a tackboard and a chalkboard at the junction thereof on a standard having spaced apart retaining flanges mounted on a connecting wall to provide spaced apart trackways, said intermediate clip comprising a body having first and second surfaces, a pair of side flanges extending outwardly and inclined with respect to said body and extending in a direction away from said first surface of said body for engagement in the tracks, a support flange extending outwardly from said body in a direction away from said second surface of said body and disposed substantially perpendicular thereto, a first retaining flange formed on said support flange and extending in a direction opposite to the direction of said body, and a second retaining flange formed on said support flange and extending therefrom in the same direction as said body.

25 16. An intermediate clip for engaging and mounting a tackboard and chalkboard at the junction thereof on a standard having spaced apart retaining flanges mounted on a connecting wall to provide spaced apart trackways, said intermediate clip comprising a body having first and second surfaces, a pair of side flanges formed on said body and at obtuse angles therewith and extending in a direction away from said first surface of said body for engagement in the tracks, a fastener receiving opening formed in said body, a support flange formed integral with said body and extending substantially perpendicular therefrom in a direction away from said second surface of said body, the outer edge of said support flange having a first retaining flange formed thereon and extending in a direction opposite to the direction of said body, a pair of ears formed on the lateral edges of said support flange and extending outwardly therefrom, and a pair of second retaining flanges formed on said ears and extending therefrom in the same direction as said body.

30 17. A bottom clip for use with a standard having a plurality of regularly spaced pockets formed therealong, said bottom clip comprising a body, a pair of hooks formed on said body and extending therefrom and out of the plane thereof for engagement in the pockets of an associated channel, a support flange formed on one end of said body and extending therefrom in a direction opposite to said hooks, and a retaining flange formed on the outer end of said support flange and extending therefrom in the same direction as said body.

35 18. A bottom clip for use with a channel having pockets formed thereon at regular intervals therealong, said bottom clip comprising a body, a pair of hooks struck from said body and extending therefrom for engagement in the pockets of an associated channel, a support flange formed integral with said body and extending substantially perpendicular thereto in a direction opposite to said hooks, a reinforcing bead formed on said support flange and extending substantially perpendicular to said body, and a retaining flange formed on the outer end of said support flange and extending substantially perpendicular

thereto in the same direction as said body, said reinforcing bead having a fastener receiving opening formed therein.

19. A top clip for use with a channel having spaced apart retaining flanges spaced from a connecting wall to provide tracks in cooperation therewith and having pockets projecting outwardly from the connecting wall in the same direction as the retaining flanges, said top clip comprising a body, first side flanges extending outwardly from said body for engagement in the tracks, said side flanges being displaced out of the plane of said body to permit said body to clear and to overlie the projecting pockets on an associated channel when said first side flanges are in the tracks, a second flange disposed substantially perpendicular to said body and extending outwardly therefrom, and a third flange formed on the outer end of said second flange and disposed therefrom in a direction opposite to

the direction of said body to engage a member to be mounted on the channel.

UNITED STATES PATENT OFFICE
CERTIFICATE OF CORRECTION

Patent No. 2,987,832

June 13, 1961

Leon F. Urbain et al.

It is hereby certified that error appears in the above numbered patent requiring correction and that the said Letters Patent should read as corrected below.

Column 11, line 71, strike out "said top clip" and insert the same after "flanges" in line 73, same column; column 14, line 17, for "May 8, 1956" read -- November 18, 1953 --.

Signed and sealed this 21st day of November 1961.

(SEAL)
